NONREFILLABLE BOTTLE

George S. Ridner, Sr., and George S. Ridner, Jr.,
Newark, N. J.

Application August 22, 1940, Serial No. 353,740

3 Claims. (Cl. 215—25)

This invention relates to non-refillable bottles, and more particularly to the valves disposed within the necks of such bottles which permit the contents to be poured therefrom but prevent liquids from being introduced into the bottles.

In order to protect their products against substitution or dilution with consequent impairment of the good will which has been built up by extensive advertising in bottled goods sold under brand names, some manufacturers have adopted the practice of marketing their products in non-refillable bottles. This is especially true in the case of manufacturers of liquors, since empty bottles bearing the government revenue stamps frequently find their way into the hands of illicit liquor vendors who fill them with an inferior grade of liquor for resale to the public under the original manufacturers' labels.

Non-refillable bottles, however, have not attained widespread use due to several reasons: (1) because of the increased cost which renders the use of non-refillable bottles prohibitive for liquids retailed in small quantities and upon a narrow margin of profit; (2) because of the mechanical difficulties inherent in the valves of such bottles which may cause them to stick or otherwise get out of order so as to obstruct the free flow of liquid; and (3) because of the opportunity afforded by the valves to tampering or fixing so as to circumvent their intended function.

The first and second of the above objections result from the relatively complicated, and hence uneconomical, valve constructions which heretofore have been proposed for non-refillable bottles. The third objection is also related more or less directly to the first two, for no matter how efficient and tamper-proof a valve may be, it will possess little commercial value unless it is positive and reliable in operation and of such simple construction as not to add materially to the cost of the bottle.

The relative efficiencies of valves for non-refillable bottles may be judged from three different standpoints: First, the inaccessibility of the working parts of the valve to tools or implements, such for example as bent wires or hooks, by which the valve may be temporarily rendered inoperative and thus allow unauthorized refilling of the bottles; second, the extent to which the valve prevents inflow when the bottle is submerged in a tank of liquid; and third, the ability of the working parts of the valve to remain seated and close the pouring passage

extending through the valve when suction is applied to the bottle.

It is an important object of our invention to provide a valve for non-refillable bottles which overcomes the previously existing objections to this type of valve and which is so constructed and arranged as to insure the tight closure of the pouring passage under any of the conditions mentioned. More particularly the invention contemplates the provision of a valve of the foregoing character which includes a gravity seated ball adapted to cooperate with two different ports located in the pouring passage so that when the bottle is tilted slightly out of vertical position to unseat the ball from one of its ports, such ball automatically rolls over into seating engagement with the other port to close the pouring passage, thus preventing the refilling of the bottle by submerging it, either in an upright or tilted position, within a tank of liquid. Furthermore, in accordance with our invention, the ball and seat are so constructed and arranged that suction applied to the mouth of the bottle draws the ball tightly against one of its seats to close the pouring passage. In the preferred form of our invention we arrange a second ball in series with the first-mentioned ball, the second ball being adapted to seat by gravity against a port in the pouring passage and provide an additional closure for this passage.

Another object of our invention is to provide a valve for non-refillable bottles which is relatively simple and inexpensive in construction and which is positive and reliable in operation.

Other objects and advantages will be apparent from the following detailed description of a preferred embodiment of the invention, reference being had to the annexed drawing in which:

Figure 1 is a view in side elevation of a valve for non-refillable bottles, indicating the position it is adapted to occupy in a bottle neck;

Figure 2 is a view in front elevation of the valve of Fig. 1;

Figure 3 is a vertical cross-sectional view of the valve on the line 3—3 of Fig. 2; and

Figure 4 is a transverse cross-sectional view on the line 4—4 of Fig. 2.

Referring to the drawing, 1 indicates a valve adapted to be locked in the neck of a non-refillable bottle 2 indicated by phantom lines in Fig. 1. This valve is preferably molded from a suitable plastic material, such for example, as Bakelite, which will not affect, or be affected by, the liquid adapted to be contained within the bottle.

The lower end of the valve comprises a cylindrical hollow plug 3 snugly fitting within and closing the bottle neck. This plug is open at its top and through its closed bottom extends a port 4. A ball 5 contained within the plug covers and closes the port when the bottle is in upright position, but is free to roll away and uncover the port to permit liquid to flow therethrough when the bottle is tilted through a pouring angle.

Above the plug 3 and connected by an inclined partition 6 is a cage 7 of generally dome shape. The bottom of the cage is provided with a port 8 opening to one side of the partition and this port is adapted to be closed by a ball 9 which seats by gravity over this port. The cage is provided with a second port 10 opening through its side wall upon that side of the partition 6 opposite to the port 8. The ports 8 and 10 are located in close proximity, being separated by a narrow web 11, and at approximately right angles to each other. The arrangement is such that tilting the bottle through a small angle causes the ball 9 to roll over the narrow web which separates the ports and seat against the port 10; and continued tilting of the bottle into pouring position results in the ball rolling into the space provided in the closed top of the dome-shaped cage (indicated by broken lines in Fig. 3) leaving both ports uncovered and in communication with each other.

The cage 7 is smaller in transverse dimension than the neck of the bottle so as to afford a suitable external clearance for the passage of the liquid. In order to seal the sides of the valve and to direct the liquid through port 4 and thence through ports 10 and 8 in succession (as indicated by arrows in Fig. 3), a pair of upright ribs 12 project outwardly from the sides of the cage and the partition 6, and these ribs make a tight fit with the inner circumference of the bottle neck.

Overlying and forming part of the top of the cage is a circular cap 13 adapted to snugly fit within the bottle neck. This cap includes a web 14 closing off a portion of the cap from that side of the valve providing communication between the ports 4 and 10. The cap is recessed upon its other side so as to provide a discharge vent 15 for liquid passing out of the valve. For locking the valve within the bottle neck, the cap is exteriorly grooved as indicated at 16, to receive a split locking ring 17 which latter is tapered in transverse cross-section, as indicated in Fig. 1. Similarly the inside of the bottle neck is provided with a circular groove 18, the arrangement being such that when the ring is assembled in the groove 16 and the valve is longitudinally inserted into the neck of the bottle, the split ring is contracted until it arrives opposite the groove 18, in which position it snaps into this groove and securely locks the valve to the bottle.

A flange 19 extends transversely from the exterior of the cage 7 so as to engage the bottle neck and serve as a guard against tampering. This flange is suitably provided with apertures 20 to allow the flow of liquid therewith. A shelf 21 bridging the discharge vent 15 is also provided on the cap 13 which serves in addition to the guard flange 19 to prevent the introduction of implements into the bottle neck. An inverted cup 22 is suspended from the under side of the inclined partition 6 above the ball 5, this cup serving to limit the movement of the ball from its seat over the port 4.

The valve just described is adapted to function as follows: When the bottle is rested in upright position the ball 5 covers the port 4 and the ball 9 covers the port 8. Upon tilting the bottle to pouring position, the ball 5 rolls into a position, limited by engagement with the inverted cup 22, so as to uncover the port 4, and the ball 9 rolls to the top of the dome 7, as indicated in broken lines in Fig. 3, to uncover the port 8. This permits liquid to pass from the bottle, through ports 4, 10 and 8, in the order named, and finally through vent 15 in the cap 13. The course of the liquid is indicated by dotted line arrows in Fig. 3.

By reason of the guard flange 19, the balls 5 and 9 are inaccessible to wires, prongs or other implements inserted downwardly through the neck of the bottle. These balls provide positive checks against refilling the bottle, when once emptied, under any conditions. The attempted introduction of liquid into the bottle when the latter is in an upright position causes the ball 9 to move from closing position with respect to the port 8 into closing position with relation to the port 10 to block the downward passage of the liquid. Even should the ball 9 in some manner be raised into the top of the cage 7 to open both ports 8 and 10, this would still be insufficient because ball 5 would prevent the flow of liquid into the bottle through the port 4.

When the bottle is submerged in a generally horizontal position within a tank of liquid, the ball 9 seats either over the port 8 or over the port 10, depending upon how the bottle is turned, so that in any event either the escape of the displaced air from the bottle or the pressure of the liquid entering the valve will hold the ball upon its seat and interrupt the flow of liquid.

By applying a vacuum to the neck of the bottle, the ball 9 is sucked tightly down into seating engagement with the port 8 so as to preclude the passage of liquid into the bottle through this port.

From the foregoing description of a preferred embodiment of our invention it will be apparent that we have devised a valve for non-refillable bottles which is simple, reliable and fool-proof in operation and which lends itself to economical manufacture. We are aware that changes in the form, construction, arrangement and combination of the various parts of our valve may be made and substituted for those herein shown and described without departing from the nature and principle of our invention, as defined in the following claims:

We claim:

1. A valve for non-refillable bottles comprising a plug adapted to fit within and close the neck of a bottle, a port provided by said plug communicating with the open neck of the bottle, a gravity-seated ball normally overlying and closing said port, a hollow cage located above said plug and of smaller maximum diameter than the plug, communicating ports opening through the bottom and side walls of said cage, said last-mentioned ports being located closely adjacent and at approximately right-angles to each other, enlargements upon the exterior of the cage adapted to engage the bottle neck and close off external communication between the cage ports, a closure member adapted to seat against and close either of said last-mentioned ports, the top of said cage providing clearance to receive and retain said closure member out of obstructing relation to both of said last-mentioned ports to

permit the flow of liquid therebetween, and a partition extending between the plug and the cage, said partition being so constructed and arranged as to provide separate passages extending between the first-mentioned port and the side-wall port of the cage and between the bottom-wall port of the cage and the open neck of the bottle.

2. A valve for non-refillable bottles comprising a hollow plug adapted to fit within and close the neck of a bottle, a port provided by said plug communicating with the open neck of the bottle, a gravity-seated ball normally overlying and closing said port, a hollow cage located above said plug and of smaller maximum diameter than the plug, communicating ports opening through the bottom and side walls of said cage, said last-mentioned ports being located closely adjacent and at approximately right-angles to each other, enlargements upon the exterior of the cage adapted to engage the bottle neck and close off external communication between the cage ports, a second gravity-seated ball adapted to seat against and close either of said last-mentioned ports, the top of said cage providing clearance to receive and retain said second ball out of obstructing relation to both of said last mentioned ports to permit the flow of liquid therebetween, a partition extending between the plug and the cage, said partition being so constructed and arranged as to provide separate passages extending between the first-mentioned port and the side-wall port of the cage and between the bottom-wall port of the cage and the open neck of the bottle, and an apertured guard extending laterally from said cage to prevent access to said balls.

3. A valve for non-refillable bottles comprising a hollow, cylindrical plug member, a hollow cage located above the plug member and a cylin-

drical cap member located above the cage, said plug member and cap member corresponding in diameter to the diameter of the neck of a bottle in which the valve is to be inserted and said cage being of smaller diameter than said plug and cap members, a port opening centrally through the bottom of the plug member and adapted to communicate with the open neck of the bottle, a gravity-seated ball normally closing said port, a cover partially closing the top of the plug and overhanging said ball, said cover providing a laterally-offset outlet through the top of the plug member, ports opening through the bottom and side walls of the cage and located closely adjacent and at approximately right-angles to each other, enlargements upon the exterior of the cage adapted to engage the bottle neck and close off external communication between the cage ports, a second gravity-seated ball adapted to roll from normal closing position with respect to the bottom port to the side-wall port of the cage, the top of said cage being formed to receive and retain said second ball out of obstructing relation to both of said cage ports in bottle-pouring position to permit the flow of liquid therebetween, a partition member extending between the cage and the plug cover and corresponding in width to the diameter of the plug and cap members, said partition member being so arranged as to define with the neck of the bottle a closed passageway extending between the outlet in the top of the plug member and the side-wall port of the cage, an opening through the cap member providing communication with the bottom port in the cage on the opposite side of the partition from the side port of the cage, and means for locking said valve within the neck of a bottle.
